UNITED STATES PATENT OFFICE.

OLOF A. NORLUND AND WILLIAM K. WAKENHUT, OF WILLIAMSPORT, PENNSYLVANIA.

ICE-CREEPER.

SPECIFICATION forming part of Letters Patent No. 784,119, dated March 7, 1905.

Application filed February 25, 1904. Serial No. 195,201.

To all whom it may concern:

Be it known that we, OLOF A. NORLUND and WILLIAM K. WAKENHUT, residents of Williamsport, in the county of Lycoming and State 5 of Pennsylvania, have invented certain new and useful Improvements in Ice-Creepers; and we do hereby declare the following to be a full, clear, and exact description of the invention, such as will enable others skilled in the art to 10 to which it appertains to make and use the same.

Our invention relates to improvements in ice-creepers, the object of the invention being to provide improved construction of creeper and improved means for securing the 15 same to the heel of a boot or shoe; and it consists in certain novel features of construction and combinations and arrangements of parts, as will be more fully hereinafter described, and pointed out in the claims.

20 In the accompanying drawings, Figure 1 is a bottom plan view illustrating our improvements secured to the heel of a boot or shoe. Fig. 2 is a view in longitudinal section. Fig. 3 is a view in plan, showing the device in its 25 unlocked position; and Figs. 4 and 5 are views of a modification.

1 represents a sheet-metal plate of the general shape of boot or shoe heel and having integral prongs 2 at its straight edge adapted 30 to be forced into the forward edge of the heel by our improved clamping mechanism, which will now be described.

An approximately S-shaped lever 3 is pivotally secured at one end by a rivet 4 to the 35 plate 1 near its center, and the outer end of the lever is twisted and bent at right angles, forming a finger-hold 5 at one edge of the plate to facilitate manipulation of the lever 3.

6 represents a slotted bar having a clamp- 40 ing-prong 7 at one end to engage the rear edge of the heel. A headed rivet 8 in plate 1 is located in the slot 9 of bar 6, and the latter has secured therein a pin 10, one end of which is located in a slot 11 in plate 1, and the 45 other end projects below bar 6 and is adapted to enter any of a series of holes 12 in a flat spring-link 13, pivotally secured to lever 3 at its bend nearest its pivotal point. It will be seen that by raising spring-link 13 from

pin 10 the bar 6 can be moved to locate the 50 pin 10 in another of the openings 12, and thereby adjust the clamp to fit other sizes of heels.

The plate 1 is shown provided with four calks or points 14, although any desired number may be employed, one of which being preferably located to form a stop for the lever 3 in clamping position, and said lever 3 and plate 1 are made with openings alined when the lever is in clamping position to receive a 60 screw, tack, or other like securing device 15, which is driven into the heel to permanently secure the creeper in place. This screw or tack 15 is only desirable where the creeper is to remain on the heel for an indefinite period 65 and is not used where the creeper is to be often removed and replaced.

In Figs. 4 and 5 a modification is shown in which but three calks are employed, and the prong 16 of sliding bar 6 engages the inner 70 edge of the heel, a prong 17, integral with plate 1, engaging the rear edge of the heel. The bar 6 in this form has the spring-link 13 pivotally connected thereto, and the lever 3 carries the pin 10 to enter any of the holes 12 75 in said link.

The operation of both forms of creeper is as follows: The lever 3 is thrown to its extreme open position and plate 1 placed against the heel, with the prongs of the plate and 80 sliding bar 6 against the sides thereof. The lever 3 is then forced to its locking position, which movement draws inward the sliding bar 6 and clamps the heel between the fixed and movable prongs, and when the lever is moved 85 far enough to swing its connection with the spring-link 13 past the line of its pivot the several parts will be secured in such position.

Slight changes might be made in the general form and arrangement of the several 90 parts described without departing from the spirit and scope of our invention, and hence we do not restrict ourselves to the precise details set forth, but consider ourselves at liberty to make such slight changes and alterations as fairly fall within the spirit and scope 95 of our invention.

Having fully described our invention, what

we claim as new, and desire to secure by Letters Patent, is—

1. In an ice-creeper, the combination with a plate having a fixed prong, of a sliding bar having a prong, and a lever pivoted to the plate, said bar and lever constituting movable members on the plate, and a link pivotally connected to one of said members and having a series of openings to receive in any of them a pin or projection on the other movable member.

2. In an ice-creeper, the combination with a plate having a fixed prong, of a sliding bar having a prong, a lever pivotally connected with the plate, said sliding bar and lever constituting movable members on the plate, and a spring-link pivotally connected at one end to one member and having a series of openings at its other end to receive in any of them a pin or projection on the other movable member.

3. In an ice-creeper, the combination with a slotted plate having calks thereon and a prong at one end, of a slotted bar at the other end of the plate having a prong thereon, a headed lug or rivet on the plate and projecting through the slot in the bar, and a pin on the bar pro-

jecting into the slot in the plate and the other end of said pin projecting below the bar, a flat perforated spring-link pivotally connected at one end to the bar by means of the pin entering one of its perforations, an S-shaped lever pivotally secured at one end to the plate, and pivotally secured to the spring-link at the bend in the S-shaped lever nearest its pivotal point.

4. In an ice-creeper, the combination with a plate having a prong thereon, of a sliding bar carrying a prong, an S-shaped lever pivoted to the plate, a link connecting the lever and sliding bar, and said plate and lever having openings therein which align when the lever is in its locked position to receive a screw or like device projected through the aligned openings into the heel of a boot or shoe and permanently secure the creeper in place.

In testimony whereof we have signed this specification in the presence of two subscribing witnesses.

OLOF A. NORLUND.

WILLIAM K. WAKENHUT.
